UNITED STATES PATENT OFFICE.

GEORGE W. GOMBER, OF CONYNGHAM, PENNSYLVANIA, ASSIGNOR TO STANDARD VENDING MACHINE COMPANY, OF HAZLETON, PENNSYLVANIA, A CORPORATION OF PENNSYLVANIA.

DESIGN FOR A FLY-SWATTER.

48,714.

Specification for Design.

Patented Mar. 14, 1916.

Application filed October 30, 1915. Serial No. 58,924. Term of patent 7 years.

To all whom it may concern:

Be it known that I, GEORGE W. GOMBER, a citizen of the United States, residing at Conyngham, in the county of Luzerne and State of Pennsylvania, have invented a new, original, and ornamental Design for a Fly-Swatter, of which the following is a specification.

Referring to the accompanying drawing, the figure is a plan view of a fly swatter showing my new design. The opposite side is of exactly the same design.

Copies of this patent may be obtained for five cents each, by addressing the "Commissioner of Patents, Washington, D. C."

I claim—

The ornamental design for a fly swatter substantially as shown.

In testimony that I claim the foregoing as my own, I have hereto affixed my signature in the presence of two witnesses.

GEORGE W. GOMBER.
